Sebastião H. Lucar - Macau, P. R.

Lillian Barto.

The laborer, referred to in these "Notes" below, was an
making part of the same, containing a description in the words
of the said laborer, and the basis, himself, of his improvement,
in the construction of working notes.

To all whom these presents shall come.

Be it known that I, Abbotton H. Davis, of Macungy, in the County of Lehigh and State of Pennsylvania, have invented, a new and useful improvement in the manner of constructing "Breaking Stones" that are to be loaded with coal ash fuel; and that the following is a full and exact description of the construction and mode of operation, as invented by me. The nature of my invention is such, as to present a combination of parts, which may have been already used separately and singly in the construction of Stones, but not in the united arrangement wherein which I now present them, as being better calculated for the combustion of coal ash fuel, and particularly anthracite or stone coal, when augered, which I have invented intended to be used for cooking; the manner of constructing which is fully set forth in the following description in which the entire of a square plate which is to form the hearth, is supported upon feet at each corner, leaving a long opening from what is to be the front to the back side, this opening is covered with a plate having along edge of four corners bevelled lengthwise, at such an angle apart, as to give the largest recess, for receiving the combustion, which is to be made with the receiver in a funnel shape, and to be made recessed to the lower side of the plate, so as to project above the top of the opening, in

77.

to be firmly secured on the top of the plates, and towards the back end, a perpendicular cylinder open at each end the circumference may be of course made of as much or open & ornamental work, in the casting thereof as may be desired and the diameter proportioned to that of the inner or enclosed cylinder for holding the fuel for combustion which must be proportioned to the size and store required for. This inner cylinder is to be supported upon flanges from the interior of the surrounding one projecting therefrom, at such a distance from the hearth as to allow for a straight opening in the latter in front; and upon these same flanges is to be supported just the grate & over it the inner cylinder. The grate is constructed of two semi-circles placed horizontally together; the front one being moveable upon a hinge joint, so as to fall down in front; where the pin or rivet upon by which it is supported being the means by which the grate is discharged of its contents for cleaning. The outer cylinder is to be constructed at its top, with the lower plates of the stove, which is to be constructed above it for the reception of the cooking apparatus, being additionally supported by two pillars at each end. These pillars will be somewhat taller than the cylinder because the lower plate is to descend by a step from them, to the cylinder, so as by leaving a considerable space and space between the bottom of the cylinder & the top of the plates, intended as a air chamber, for that which is air tight and furnished with a door or door for the supply of fuel. also the top of the inner cylinder will rise somewhat above that of the outer and need be riveted to a plate to plate which will give them exactness of the outer at a great distance apart.

The bottom plate being of mottled, so as to leave a hollow-space between them. The stone above the plates will present the appearance of the ordinary plate stone, being of a long shape and the cylinder in the centre of the bottom plate.

The stone which is placed over the air-chamber occupies nearly the entire length, with the exception of a hollow-space between the two plates of it and the outside of the stone, the latter being cut outwards in the usual way. These form the draught passages for the circulation of the heat &c. and are to be closed by means of dampers, turning on central valves being furnished to each end of the stone. The side projecting beyond the front side of the stone presents a square head, to which is fitted a iron handle, by which the aperture is opened or closed as the draught is desired. The stone has doors on each side above it, the draught passages between the top place thereof and that of the stone, to the aperture for the smoke which is placed in the middle; and at each side of the top plate are holes for corking vessels; and the ordinary fixtures of cleaning or committing vessels to be used. For the purpose of preventing the gas from creeping into the vessels are corking or bunging. Take a pipe with a flange around its upper edge to hang within the hole from the top plate; and into this fit the bottom of the corking vessel; or the vessel may have a rim to it, and a cover a flange as high up as it may be desired that the vessel shall descend into the space between the top plates, in which flange it will rest upon the top pipe when corked, the opening of the pipe.

The stone is to be built into the stone walls, one end being

80

so as to admit a rod through those over the bottom plate & hearth, furnished with screws and nuts; and as said pillars are divided longitudinally for the convenience of fastening, there will be required at top and bottom of each, a socket or cup into which the end of the pillars will rest, & the rim of which will form a stay or cheek, to the separation of the halves when they are united & set up.

Having now described the nature of the invention, and the manner in which it is carried into effect, I would have it understood that I do not claim any of the parts separately; but I do claim as my invention the combining of the various parts in the manner above described.

In testifying that the above is a full description of my improvement as invented by me I have hereunto set my hand this second day of May eighteen hundred & thirty six.
